Fig. 1

Fig. 2

FIG. 1 is a top plan view of a spectacle frame front showing my new design.

FIG. 2 is a front elevational view of FIG. 1.

The dominant features of my design reside in the portions shown in full lines being characterized by the particular elements superimposed upon the upper front of the outer ends and following the concave curve of said outer ends as indicated.

I claim:

The ornamental design for a spectacle frame front, as shown and described.
